Inventor:

Harold E. Hawkins

By F. G. Fisher

Atty.

UNITED STATES PATENT OFFICE.

HAROLD E. HAWKINS, OF KANSAS CITY, MISSOURI.

LOOSE-LEAF BOOK.

No. 904,777.

Specification of Letters Patent.

Patented Nov. 24, 1908.

Application filed September 25, 1906. Serial No. 336,155.

To all whom it may concern:

Be it known that I, HAROLD E. HAWKINS, a citizen of the United States, residing at Kansas City, in the county of Jackson and State of Missouri, have invented certain new and useful Improvements in Loose-Leaf Books, of which the following is a specification.

My invention relates to improvements in loose-leaf books; and one of my objects is to provide a simple device of this character wherein loose-leaves may be readily inserted, or from which they may be easily removed.

A further object is to arrange the several parts in such a manner that they may be readily assembled for use, or taken apart when it is necessary to repair or replace worn or broken parts.

The invention consists in the novel construction, combination, and arrangement of parts, hereinafter described, pointed out in the claims, and illustrated in the accompanying drawing, in which:

Figure 1 represents a vertical section of a loose-leaf book, provided with my improvements. Fig. 2 is an enlarged vertical section of the same in an open condition. Fig. 3 is a perspective view of a pair of hook-carrying members, forming part of the invention. Fig. 4 is a perspective view of a pair of resilient members for holding the hooks in an open or closed condition. Fig. 5 is a perspective view of a frame for holding the several parts together.

In carrying out the invention I employ a frame 1, consisting of a channel-bar having a pair of marginal grooves 2 in its upper edges.

3 designates a pair of hook-carrying members, having their outer margins pivotally arranged in grooves 2, and provided at their inner margins with longitudinal recesses 4.

5 designates a series of segmental hooks, fixed at their lower ends upon members 3.

45 The upper ends of one set of hooks have V-shaped tongues 6, adapted to engage V-shaped grooves 7 in the upper ends of the opposing members, so that when the hooks are in a closed condition they will be held in alignment with each other.

8 designates a pair of resilient members for reliably holding members 3 in engagement with grooves 2 and the hooks in an open or closed condition. Members 8 are

held from longitudinal movement by recesses 55 4, and provided with out-turned wings 9, which overlap the adjacent sides of members 3, and loops 10, which underlie the said members 3. Loops 10 limit the opening movements of the hooks by contacting with the under side of members 3, as shown in Fig. 2, and the closing movements of said hooks by contacting with the lower portion of frame 1, as shown in Fig. 1, the loops being arranged to contact with said frame 65 simultaneously with the engagement of the upper ends of the hooks.

11 designates a strip of stiff material, extending the length of frame 1, and secured to the under side thereof, by rivets 12. Said 70 strip affords convenient means for the reception of a cover 13, which may be pasted or otherwise secured thereto.

14 designates an arched top plate, extending the length of frame 1, and removably secured thereto, by its inwardly curved margins 15, which clasp the outwardly curved margins 16 of the frame. Plate 14 is provided for the purpose of covering members 3 and 8, and give a finished appearance to 80 the device, and in order to avoid interfering with the movements of the hooks, is provided with slots 17, through which said hooks extend.

Having thus described my invention, what I claim is:

1. In a device of the character described, a channel-bar, a pair of hook-carrying members pivotally engaging the same, and a resilient member engaging the adjacent edges 90 of the hook-carrying members, for the purpose described.

2. In a device of the character described, a frame having a pair of grooves, hook-carrying members pivotally engaging said 95 grooves, and a resilient member having wings overlapping the adjacent sides of the hook-carrying members and a loop interposed between the underside of said members and the frame.

3. In a device of the character described, a frame having marginal grooves, a pair of hook-carrying members pivotally engaging said grooves and provided with marginal recesses, resilient members engaging said recesses, having wings overlapping the adjacent sides of the hook-carrying members and the frame, and a top plate removably engaging

the upper portion of the frame, and provided with slots through which the hooks extend.

4. In a device of the character described, 5 a channel-bar, a pair of hook-carrying members pivotally engaging the same, a resilient member engaging the adjacent edges of the hook-carrying members, a strip of stiff ma-

terial secured to the underside of the channel-bar, and a cover secured to said strip. 10

In testimony whereof I affix my signature, in the presence of two witnesses.

HAROLD E. HAWKINS.

Witnesses:

Ross HAWKINS,

F. G. FISCHER.
